UNITED STATES PATENT OFFICE

FÉLIX FRÉDÉRIC RUAU, OF DEPTFORD, LONDON, ENGLAND, ASSIGNOR TO MOLINS
MACHINE COMPANY, LIMITED, OF LONDON, ENGLAND

APPARATUS FOR COMBING AND FEEDING TOBACCO FOR MAKING CIGARETTES AND
FOR OTHER PURPOSES

Application filed September 14, 1925, Serial No. 56,355, and in Great Britain October 24, 1924.

This invention relates to an improved apparatus for combing or regulating and feeding tobacco to cigarette making machines.

According to the invention, the apparatus comprises a hopper for the tobacco to be treated, having a discharge opening or channel which may be connected to or form a part of the cigarette machine, and a series of carded rollers, combs and brush rollers or their equivalents, so arranged that the tobacco is subjected, preferably, to a double combing or regulating to secure an uniform density, and is discharged without the employment of conveyor bands or the like. If desired, the apparatus may be arranged to subject the tobacco to more than two combings before discharge.

A side of the hopper may be mounted for oscillation and suitable means are provided 20 for driving the various rollers.

Although the invention is particularly adapted for use with cigarette making machines, it may be applied for preparing tobacco for other purposes.

25 To enable the invention to be fully understood it will now be described with reference to the accompanying drawings, in which:—

Figure 1 is an elevation of one end of a hopper constructed according to the invention, showing the driving gear, and

30 Figure 2 is an elevation of the other end thereof.

Figure 3 is a diagrammatic side elevation of the hopper partly in section and without the driving gear.

Figures 4, 5 and 6 are views of details.

Figure 7 is a diagrammatic view showing a method of operating the back of the hopper.

As shown, the hopper comprises end frames 40 1, 2, held together by tie rods 3, side pieces 4, which may be of wood, a back plate 5, and various drums and rollers mounted between the end frames. The drums and rollers form the front wall of the hopper, and the tobacco to be treated is placed between the back plate 45 5 and the drums and rollers.

Referring first to Figure 3, in which the various drums and rollers are shown diagrammatically.

The tobacco is fed by a feed roller 6 rotating in the direction of the arrow A to a carded roller 7, which in turn feeds it upwards past another carded roller 8. The roller 6 is preferably a plain metal or wooden roller and the carding on roller 8 is preferably finer than that on roller 7.

According to the invention, the apparatus 55 comprises a hopper for the tobacco to be treated, having a discharge opening or channel which may be connected to or form a part of the cigarette machine, and a series of carded rollers, combs and brush rollers or their equivalents, so arranged that the tobacco is subjected, preferably, to a double combing or regulating to secure an uniform density, and is discharged without the employment of conveyor bands or the like. If desired, the apparatus may be arranged to subject the tobacco to more than two combings before discharge.

A side of the hopper may be mounted for oscillation and suitable means are provided 20 for driving the various rollers.

Although the invention is particularly adapted for use with cigarette making machines, it may be applied for preparing tobacco for other purposes.

25 To enable the invention to be fully understood it will now be described with reference to the accompanying drawings, in which:—

Figure 1 is an elevation of one end of a hopper constructed according to the invention, showing the driving gear, and

30 Figure 2 is an elevation of the other end thereof.

Figure 3 is a diagrammatic side elevation of the hopper partly in section and without the driving gear.

Figures 4, 5 and 6 are views of details.

Figure 7 is a diagrammatic view showing a method of operating the back of the hopper.

As shown, the hopper comprises end frames 40 1, 2, held together by tie rods 3, side pieces 4, which may be of wood, a back plate 5, and various drums and rollers mounted between the end frames. The drums and rollers form the front wall of the hopper, and the tobacco to be treated is placed between the back plate 45 5 and the drums and rollers.

Referring first to Figure 3, in which the various drums and rollers are shown diagrammatically.

The tobacco is fed by a feed roller 6 rotating in the direction of the arrow A to a carded roller 7, which in turn feeds it upwards past another carded roller 8. The roller 6 is preferably a plain metal or wooden roller and the carding on roller 8 is preferably finer than that on roller 7.

According to the invention, the apparatus 55 comprises a hopper for the tobacco to be treated, having a discharge opening or channel which may be connected to or form a part of the cigarette machine, and a series of carded rollers, combs and brush rollers or their equivalents, so arranged that the tobacco is subjected, preferably, to a double combing or regulating to secure an uniform density, and is discharged without the employment of conveyor bands or the like. If desired, the apparatus may be arranged to subject the tobacco to more than two combings before discharge.

A side of the hopper may be mounted for oscillation and suitable means are provided 20 for driving the various rollers.

Although the invention is particularly adapted for use with cigarette making machines, it may be applied for preparing tobacco for other purposes.

25 To enable the invention to be fully understood it will now be described with reference to the accompanying drawings, in which:—

Figure 1 is an elevation of one end of a hopper constructed according to the invention, showing the driving gear, and

30 Figure 2 is an elevation of the other end thereof.

Figure 3 is a diagrammatic side elevation of the hopper partly in section and without the driving gear.

Figures 4, 5 and 6 are views of details.

Figure 7 is a diagrammatic view showing a method of operating the back of the hopper.

As shown, the hopper comprises end frames 40 1, 2, held together by tie rods 3, side pieces 4, which may be of wood, a back plate 5, and various drums and rollers mounted between the end frames. The drums and rollers form the front wall of the hopper, and the tobacco to be treated is placed between the back plate 45 5 and the drums and rollers.

Referring first to Figure 3, in which the various drums and rollers are shown diagrammatically.

carrying a striker 84 at its other end which vibrates the trough, the spring 85 returning the lever 82 as will be understood.

Above the roller 8 a shaft 18 is mounted 5 carrying two flaps 19 of leather or similar material which brush back any tobacco clinging to the carding and return it to the mass in the hopper.

The means for driving the feed roller 6, 10 roller 7, rollers 11, 15 and shaft 18 will now be described by reference to Figure 1.

A pulley 20 mounted on the end frame of the hopper, is driven by a belt 21 from a suitable source of power through a ratchet clutch 15 22. This arrangement enables the rest of the machine of which the hopper forms a part to be turned backwards without moving the hopper rollers.

The belt 21 is kept taut by a jockey roller 20, 23 and a spring 24, the tension of the latter being adjusted by a handle 25, which may be locked at 25a.

The drive is transmitted from the pulley 20 through a gear wheel 26 on the pulley 25 shaft, to a wheel 27 secured to a wheel 28 which in turn drives a wheel 29. The wheels 28, 29 are detachable, forming change wheels for varying the speed of the hopper relatively to the cigarette machine. Secured to the 30 spindle 53 of wheel 29 is a small wheel 30 which transmits the motion to a gear wheel 31, the spindle of the latter carrying a gear wheel 32 and a sprocket wheel 33.

The spindle of drum 7 carries a gear wheel 35 32a which is driven by the wheel 32 and a chain 34 connects the sprocket wheel 33 to a sprocket wheel 35 on the spindle of the plain roller 13.

The picker rollers 11 and 15 are driven 40 from the pulley 20 by a pulley 26 secured thereto, through the medium of a belt 37 and pulleys 38, 39 on the spindles of the rollers. An adjustable jockey pulley 40 is interposed as shown.

45 On the pulley 38 is mounted a pulley 41, which drives the top shaft 18 on which the leather flaps 19 are mounted by means of belt 43 and pulley 44.

Several of the smaller rollers are adjustable; for example, the roller 11 is carried in 50 bearings in quadrants 45, which are pivoted at 46, and locked in position by screws 47 and the other rollers may be similarly mounted. The driving gear for the remaining 55 drums and rollers will now be described with reference to Figure 2.

A sprocket wheel 48 on drum 7, which is driven by gears as already described, is connected to sprocket wheels 49, 50 on drums 12 60 and 6 by a chain 51, a chain tightener 52 being provided.

The shaft 53, Figure 1, on which gears 29, 30 are mounted passes through to the end 65 frame 2, and carries a crank pin 54. A connecting rod 55 attached to the crank pin 54

is linked at its other end to an oscillating arm 56 carrying a pawl 57. This pawl 57 engages a ratchet wheel 58 on the spindle of the top drum 8, so that the latter rotates intermittently, the drum being held by a retaining pawl or detent 59 as shown.

The back plate 5 of the hopper may be moved to press the tobacco continuously into contact with the feed roller by the following arrangement:

The back 5 which is preferably of wood is carried on metal stays 60, secured upon a spindle 61, rotating in bearings 62. On one end of the spindle 61 a quadrant 63 having ratchet teeth is fitted and a pawl 64, operated from the spindle of drum 7, engages the teeth and gradually swings up the back plate 5 to the vertical position. A locking pawl 65 is also provided.

The pawl 64 is pivoted to a link 68, pivoted at 69 and connected by a rod 67 to a crank pin 66 on the spindle of drum 7.

The pawl 64 is here shown as pivoted about mid-way of link 68, but this position may be varied to alter the rate of feeding.

The combs 10, 14 are mounted in bearings 70 in the frames and are fitted at one end with levers 71. Springs 72 attached to the levers keep the combs in engagement with the carded drums. The top carded drum 8 is mounted in adjustable bearings to enable the space through which the tobacco passes to be varied, and a brake band 73 is also fitted to prevent overrunning. The drum 8 may rotate continuously if desired.

In Figure 6 an alternative method of moving the hopper back plate 5 is shown. The plate 5 is hinged at 74 and arm 75 which is slowly rotated by ratchet gear presses the back forward as previously described.

In addition to this, an oscillating motion is imparted to the hopper back by means of a rack bar 76, one end of which is connected to a crank pin 78 on a crank 79, the teeth of the rack engaging a bar 77 on the hopper back. The crank 79 is carried on a shaft 80 driven from any suitable part of the gearing.

A weight 81 on a cord passing over a pulley 82 holds the bar 77 in engagement with the teeth of the rack. As the shaft 80 rotates, the rack bar moves backwards and forwards and in conjunction with the weight causes the hopper back to oscillate.

Each time the ratchet gear moves the back inwards, the bar 77 moves forward one tooth of the rack and continues to oscillate.

What I claim as my invention and desire to secure by Letters Patent is:—

1. An apparatus for feeding tobacco to a cigarette making machine which comprises, in combination with a positively driven carded combing roller, a second positively driven roller adapted to brush superfluous tobacco from the surface of the said combing roller, a positively driven distributor in the

form of a carded roller mounted below and forwardly of the said combing roller, a yieldingly controlled comb adapted to bear upon the forward portion of said combing roller,
5 a picker roller located above said distributor and adapted to mesh with the teeth of said comb, and a picker roller and comb mounted directly above the trough of the machine and in operative engagement with the distributor
10 for the purpose hereinbefore set forth.

2. Apparatus for feeding tobacco to a filling trough of a continuous rod type cigarette machine comprising, in combination, a carded combing roller adapted to receive a supply
15 of tobacco, means for removing the tobacco from said combing roller, and a carded distributing roller for receiving the removed tobacco directly from the combing roller and delivering the same directly and uniformly
20 to the filling trough of the machine.

3. Apparatus for feeding tobacco to a filling trough of a continuous rod type cigarette machine comprising, in combination, a carded combing roller adapted to receive a supply
25 of tobacco, a picker roller for removing the tobacco from said combing roller, a conveyor comprising a carded distributing roller interposed between the combing roller and the filling trough for receiving the removed tobacco directly from the combing roller, and
30 a picker roller mounted above the filling trough for removing tobacco from the conveyor to the trough.

In witness whereof I have hereunto set my
35 hand.

FÉLIX FRÉDÉRIC RUAU.
